UNITED STATES PATENT OFFICE.

CHARLES SEEFIELD, OF LOMIRA, WISCONSIN.

IMPROVEMENT IN GATES.

Specification forming part of Letters Patent No. **59,084**, dated October 23, 1866.

To all whom it may concern:

Be it known that I, CHARLES SEEFIELD, of Lomira, in the county of Dodge and State of Wisconsin, have invented a new and useful Improvement in Gates; and I do hereby declare that the following is a full, clear, and exact description of the construction and operation of the same, reference being had to the annexed drawings, making a part of this specification.

A, foundation-sill; B B, gate-posts; C, gate; D, bar with groove for gate to slide in; E, lever to raise the bar D; F, platform for weight; e, cross-sill attached to E for platform to rest upon; h, standard on which E rests and works; f, standard on which D rests and works; g, groove for gate to run in; o, wheels to carry the gate; n, slot in sill for E, &c., to work in.

Description of Working.

By placing weight upon the platform F,

which weight operates the lever E, and the lever E, operating upon the bar D, inclines the bar to the rear, and the gate runs back or opens of its own gravity. By raising the weight from the platform F the draft of the gate brings down the lever E, which inclines the bar D forward, and the gate closes of its own gravity.

I claim—

The arrangement of the platform F with the lever E, with bar D, so operated by weight on the platform F as to give the bar D the requisite inclination, so that the gate opens and closes by its gravity.

CHARLES SEEFIELD.
